UNITED STATES PATENT OFFICE.

CARL FREDERICK LENGFELD, FREDERICK OTTO LENGFELD, AND JOHN JOSEPH McHUGH, OF SAN FRANCISCO, CALIFORNIA.

VALVE LIFTER.

Application filed March 16, 1921. Serial No. 452,813.

To all whom it may concern:

Be it known that we, CARL FREDERICK LENGFELD, FREDERICK OTTO LENGFELD, and JOHN JOSEPH McHUGH, citizens of the 5 United States, and residents of San Francisco, county of San Francisco, and State of California, have invented a new and useful Valve Lifter, of which the following is a specification.

- 10 The present invention relates to improvements in valve spring lifting devices and is intended to be used principally in connection with Ford automobiles. It will, therefore, be described in the following with particular reference to Ford automobiles, although we do not wish to confine ourselves to this 15 type of automobiles exclusively but wish to secure protection for our invention in connection with any automobile in which similar conditions prevail and on which it may be used to advantage.

The principal object of our invention is to provide a valve spring lifting device by means of which four valve springs may be 20 lifted at a time and which will interfere in no way with the operations necessary for the removal or the grinding of the valve. A further object is to provide a valve spring lifter that does not interfere with the intake 25 and exhaust manifolds or the carburetor and has no working parts below the valve spring seat and thus does not offer any obstacle to the fingers of the operator in extracting the pin supporting the spring seat. A further 30 object is to provide a lifter that may remain in its place while the work desired to be done on the four valves concerned is performed and thus does away with any readjusting of the device for the replacing 35 of the valve. A further object is the utilizing of the two waterholes which are disposed between the first and the second and between the third and the fourth of the 40 cylinders of the Ford engine to provide a strong and positive hold for our device so that there is no chance for the same becoming loose or dislocated while the work is 45 being done on the valves.

We attain these objects by means of the 50 mechanism illustrated in the accompanying drawing in which Figure (1) represents a front view of the cylinder casing of a Ford engine, the cylinder head being removed, having our device attached thereto, and 55 Figure (2) a plan view of our device, indi-

cating the location of the different parts of the cylinder casing in dotted lines.

Referring to the drawing more particularly, it will be seen that in the engine (1) of a Ford automobile the cam shaft (2) 60 actuates the push rods (3) and through them the valves (4) consisting of the valve stems (6) and the valve heads (7). Between the upper part of the engine casing and a washer (8), hereinafter referred to as the 65 spring seat, a spring (9) is interposed. The spring seat (8) is held in place by a pin (11) penetrating the valve stem below said spring seat. In operation a cam (12) on the cam shaft pushes the valve upward, while 70 the spring forces it downward again as soon as the cam permits of a downward motion. In order to remove the valve or to gain free access to the same it is necessary to remove the pin supporting the spring seat. 75 whereupon the valve may be withdrawn upwardly.

Our lifting device (16) is designed to facilitate the removal of the pin and to enable the operator to handle four valves simultaneously. As may be seen from the drawing, our device consists of a clamp (17), comprising a substantially U shaped rigid yoke (18), consisting of a substantially vertical member (19), an upper horizontal arm (21) 80 and a lower horizontal arm (22). The upper arm carries at its end a lug (23) having a vertical, threaded hole (24) into which fits the screw 26 having a wing (27) at its upper end. The lower arm (22) carries a horizontal metal plate (28), co-extensive in length with about one-half of the engine casing. At its working edge (29), as shown in Figure (2), it is provided with four slots (31) ending into circular recesses (32) which are 85 spaced with reference to each other so as to correspond to the distances between four adjoining valve stems in the Ford car. While in a Ford car the valve stems are not all evenly spaced, there being a larger space between the fourth and the fifth than between the others, the spacing is even in two groups of four each, and our device will be adapted to fit on either group of four.

The vertical member (19) is spaced sufficiently far from the ends of the horizontal arms so as to clear the intake and exhaust manifolds (33) and (34).

It will be seen that when in place as shown in Figure (1), the screw (26) is not verti- 110

- 5 cally aligned with the valve stems but is ar-
ranged parallel to the same in a plane some-
what nearer the center line of the engine
casing. The object of this arrangement is,
5 that in this manner we can utilize two holes
(36) that are provided in the top of the en-
gine casing of a Ford automobile in connec-
tion with the water cooling system. One
of these holes is disposed between the
10 first and second cylinders, almost mid-
ways between the center line of the cyl-
inders and the center line of the valve stems,
and the second hole on the same longitudinal
line between the third and the fourth cyl-
15 ders. By making the upper arm a little
longer than the lower arm we can utilize
these holes as a support for the screw with-
out affecting the horizontal position of the
plate.
20 In actual use our device works as follows:
After removal of the cylinder head insert
the tip of the screw (26) into the water hole
(36) between the first and second cylinders,
then slip the plate of the lower arm on the
25 four valve stems of the two first cylinders,
between the valve spring seats and their
supporting pins, and raise the seats by
tightening the screw; withdraw the pins and
do whatever work is required on any of the
four valves. After completing all the work
30 the valves may be returned to their respec-
tive places and the pins inserted again, the
springs remaining undisturbed during the
entire operation. The clamp is now relaxed
35 by unscrewing screws (26) and may then be
removed.

We claim:

A valve spring seat lifting device for an
internal combustion engine comprising a
yoke consisting of a vertical body member
40 and two horizontal arms extending there-
from in substantially parallel relation, the
lower arm having a plate secured thereon
with a plurality of slots adapted to sim-
45 taneously engage a plurality of valve spring
seats, and the upper arm having a vertical
screw associated therewith for clamping the
yoke to the engine casing, and being longer
50 than the lower arm so that the screw engages
the engine casing rearwardly of the valve
line.
